UNITED STATES PATENT OFFICE.

WALTER R. HOLSEY, OF CORSICANA, TEXAS, ASSIGNOR OF ONE-HALF TO P. F. HALBERT, E. R. GLOVER, W. R. KENNER, J. T. MONTFORT, AND L. L. HOLSEY, ALL OF CORSICANA, TEXAS, AND S. W. JOHNSON, OF DALLAS, TEXAS.

KNEE-PAD.

1,155,491.

Specification of Letters Patent.

Patented Oct. 5, 1915.

Application filed May 3, 1915. Serial No. 25,381.

To all whom it may concern:

Be it known that I, WALTER R. HOLSEY, a citizen of the United States, residing at Corsicana, in the county of Navarro and 5 State of Texas, have invented certain new and useful Improvements in Knee-Pads, of which the following is a specification.

My invention has relation to a knee pad or rest for berry or cotton pickers or for 10 other workers who are obliged to remain in a kneeling position and in such connection it relates more particularly to the arrangement and construction of such a pad or rest.

In devices of this character it is desirable 15 that there be few parts, that there be only such metal parts in the construction as are necessary to secure the yielding support for the knee, and that the parts be strong and of simple construction to insure cheapness as 20 well as durability for the device.

I attain all of these desirable features by 25 providing a knee pad or rest consisting of substantially but two elements, namely a spring frame constructed of one piece of strong spring wire and a bag or sack to receive the knee and arranged to carry the spring frame and to permit of the same being secured to the leg of the wearer. The 30 bag or sack being of textile material and subject to wear and tear is readily removable from the spring frame and from the straps or fastening means which secure the bag or sack to the leg of the wearer.

As an additional feature the spring frame 35 is provided with a shield plate comprising a metallic base having a forwardly and upwardly projecting front edge, whereby the wearer may crawl through weeds, etc. during the operation of picking, without being 40 impeded in his progress.

The nature and scope of my invention will 45 be more fully understood from the following description taken in connection with the accompanying drawings, forming part hereof, in which,—

Figure 1, is a perspective view of a knee pad embodying main features of my invention. Fig. 2 is a cross sectional view of the same, and Fig. 3, is a perspective view of 50 modified form of spring frame removed from the sack or bag.

Referring to the drawings, the spring member of the pad consists of a substantially rectangular base 1, formed of spring

wire of relatively coarse gage. Approximately midway of the ends of the base, an upright portion 2 of the wire extends upward from each side, each portion being coiled as at 3 and then projected backward as at 4 and downward as at 5 and then laterally as at 6. As thus constructed the spring member comprises a flat base frame 1, the two side spring arms 4 and the rear curved arm 6 all integrally connected. In Fig. 1 the uprights 2 are welded as at 2^a to frame 1. In Fig. 3, however, a single strand of wire is bent or convoluted to form the different portions of the spring member, and T shaped sleeves 7 are used to form the connections between uprights 2 and base frame 1. In conjunction with the spring member thus constructed and arranged there is provided a sack or bag having a pouch 8 fitting over the rear curved arm 6 and side spring arms 4 of the spring member. The flap 9 of the bag or sack projects upwardly and forwardly beyond the springs 3 and is provided with a strap 10 for fastening the flap of the bag to the leg of the wearer above the knee. A strap 11 carried by pouch 8 serves to secure the pouch 8, and the inclosed spring member to the leg of the wearer below the knee.

To the bottom of the base frame 1 is secured a metallic plate 12 having a forwardly and upwardly extending shield 13. The plate 12 is provided with the clips 14 integral with plate 12 and which are bent around the sides and rear end of base frame 1 to secure the plate 12 to said frame 1. The 85 plate 12 with its guard or shield 13 permits the pad to rest flat upon the ground and prevents weeds, briars, etc., from interfering with the progress of the worker over the ground.

When the bag or sack wears out, the straps 10 and 11 may be readily detached from the flap 9 and pouch 8 and replaced upon a new bag or sack. The old sack may be readily removed from the spring member and the new sack placed on said member.

Having thus described the nature and objects of my invention what I claim as new and desire to secure by Letters Patent, is,—

1. In a device of the character described, a spring member comprising a rectangular base formed of spring wire, uprights formed integrally therewith and extending upward

from the sides, side spring arms formed integrally with and extending rearwardly from said uprights, said side arms joined by a downwardly and laterally projecting arm, a bag having a pouch inclosing the rear and side arms and a flap extending upwardly and forwardly therefrom in combination with means removable from the bag and adapted to fasten the pouch and the flap to the wearer.

2. In a device of the character described, a spring member formed of a single spring wire and comprising a rectangular base, uprights formed integrally with and projecting upward from the sides of the base, side spring arms formed integrally with and extending rearwardly from said uprights, and a laterally projecting arm formed integrally with the side arms and projecting downwardly and laterally therefrom.

3. In a device of the character described,

a spring member formed of a single spring wire and comprising a rectangular base, uprights formed integrally with and projecting upward from the sides of the base, side spring arms formed integrally with and extending rearwardly from said uprights, and a laterally projecting arm formed integrally with the side arms and projecting downwardly and laterally therefrom, combined with a base plate having an upwardly and forwardly projecting front edge said base plate united to the base and extending beneath and in front of the same.

In testimony whereof I have signed my name to this specification in the presence of two subscribing witnesses.

WALTER R. HOLSEY.
